UNITED STATES PATENT OFFICE.

HARRISON J. L. FRANK, OF DETROIT, MICHIGAN, ASSIGNOR TO MUTUAL ELECTRIC AND MACHINE COMPANY, OF DETROIT, MICHIGAN, A CORPORATION OF WEST VIRGINIA.

SAFETY SWITCH.

Application filed May 5, 1922. Serial No. 558,578.

This invention relates to safety switches which comprise boxes in which the circuit closing devices are mounted and in which such devices are inaccessible so long as the 5 circuit is closed, and the object of this invention is to provide a safety switch embodying removable fuses which shall be simple in construction, which can be made at comparatively low cost, in which the fuses 10 are accessible only after the circuits are broken, and in which the cover which gives access to the fuses must be closed before the circuits can be closed.

This invention consists in the details of 15 construction illustrated in the accompanying drawings and particularly pointed out in the claims.

In the drawings, Fig. 1 is a side elevation of this improved safety switch. Figs. 2 and 20 3 are sections on the lines 2—2 and 3—3 of Fig. 1 respectively. Fig. 4 is a section on line 4—4 of Fig. 2 with the fuse shown in elevation. Fig. 5 is a section on line 5—5 of Fig. 2 with the fuse omitted. Figs. 6 and 25 7 are sections on the lines 6—6 and 7—7 of Fig. 3 respectively. Fig. 8 is another side elevation of the switch with a slightly modified cover. Fig. 9 is a section of the pivotal mounting of the operating handle. Fig. 10 30 is a section on the line 10—10 of Fig. 8.

Similar reference characters refer to like parts throughout the several views.

The box shown in the drawings is preferably of metal and comprises a bottom 1, sides 35 2 and 3, ends 4 and 5, the latter preferably having an opening 46 for wires, and the cover 7—8, the part 8 being secured to the box in any desired manner, as by the screws 9, (Fig. 6) and the part 7 being hinged to 40 the part 8. Within the box and secured to the sides 2 and 3 thereof by means of brackets 11 is a slab 10 of slate or other good insulating material.

A pair of disks 15 and 16, on opposite 45 sides of the side 2, are secured together by the screws 56. It is usually difficult to permanently journal a shaft or other rotatable member in a sheet of metal, but I overcome this difficulty by forming the hole in the side 50 2 quite large and by securing a third disk 57 between the disks 15 and 16 by means of the screws 56, as shown in Fig. 9. These screws preferably pass through the handle

17 and into the bail 52. To these disks is secured the operating handle 17. One end 55 18 of the handle 17 extends over the cover 7—8 and is normally held over the cover 7 by means of a spring latch 19 which may be integral with the plate 20 which extends through a slot (not shown) in the cover 7 and is provided with a hole 21 through which the hasp of a pad-lock may extend. Rivets 22 secure the plate 20 and latch 19 to the side 2 of the box.

Mounted on one side of the slab 10 are 65 fuse clips 24, 25, 26 and 27 and on the other side is a knife blade switch consisting of the pedestals 28 and 29 between which the knife blades 31 and 32 are pivoted, and the clips 33 and 34. The arrangement of these clips 70 and switches is so much a matter of choice that the parts shown in the drawing may be taken merely as an example. The line wires 35 and 36 may connect to the pedestals 28 and 29 by means of nuts 37, and when the circuit is closed, the current will pass over the blades 31 and 32, clips 33 and 34, bolts 38 through the slab to the fuse clips 24 and 25, thence through fuses 39 and 40 to the fuse clips 26 and 27, and bolts 42 through the 75 slab to the load wires 43 and 44 which are secured in place by the nuts 45. This permits all the load and line wires to pass through the hole 46 in the end 4 of the box.

A bar 47 of insulating material connects 80 the knife blades 31 and 32 and connected thereto is a bracket 48 (Fig. 6) which carries the shield 49, also preferably of insulating material. A hook 50 extends from the bar 47 and engages the bail 52 which is connected to the disks 15 and 16 and to the handle 17, so that the knife blades 31 and 32 may be swung into or out of engagement with the clips 33 and 34 by the handle 17 without the box being opened. While the handle is normally held in the closed-circuit 85 position by the latch, a spring 58 on the screw 59 as shown in Fig. 7 normally tends to swing the bail and lever back to the position shown in dotted lines in Fig. 6, and this movement is caused by the spring as soon as the latch releases the handle.

The cover 7—8 is preferably a section of a 90 cylinder with the center of the cylinder co-axial with the axis of the bail 52 and handle 17. As stated before, a part 18 of the han-

2
dle 17 extends over the cover and the result is that when the handle is moved to the position indicated in Fig. 1 the part 7 of the cover cannot be lifted, nor can the handle 5 be swung to circuit closing position until the cover has been swung back to the position shown in solid lines in Fig. 1.

The slab 10 of slate or other non-conducting material can be made very small, that is, 10 not over one-half of the ordinary size necessary in switch boxes where the slab forms the bottom of the box. In the present case the switch proper is on one side of the slab and the fuse on the other and the slab is up- 15 right in the box when it rests on its bottom and divides the box into two compartments. This location of the slab not only saves material, but it permits direct connection through the slab between the clips and fuse 20 holders so that the same bolts will act as electrical connectors and will secure the parts in position.

The shield 49, preferably of non-conducting material such as vulcanite or gutta 25 percha, is of such length, as indicated in Fig. 6, that at no time can fingers be inserted between the shield and the upper part of the slab 10, and it always extends into the space 30 between the top of the slab 10 and the hinge 31 of the cover. As this space need not be over one-quarter inch deep, it is impossible to insert the fingers to touch the knife blades 32.

In Figs. 8 and 10 a slightly modified construction of box is shown. The sides, ends and bottom of the box are the same as before described and the part 8 of the cover may also be of the same construction as that shown in Fig. 1. The part 70 of the cover, 40 however, is shown formed with a flange 71 which is a segment of a cylinder whose center when this cover is down is the axis of the handle 72. This handle is provided with a pin 73 which extends inwardly over this 45 flange 71 and thereby prevents the cover 70 from being swung open until the handle has been swung to the left in Fig. 8 to open-circuit position.

In order to prevent the cover 70 from being swung too far, a small bracket or projection 74 is secured thereon to engage the part 8 of the cover and thus prevent the part 70 from being swung back so far that the flange 71 will be moved out of the path of the pin 73, for otherwise the handle could be swung forward with its pin 73 passing beneath the flange 71. In the present case the box must be closed before the handle can be swung forward to close the electric circuit and the handle must be swung back to open the circuit before the box can be opened to give access to the fuses. In both cases the fuses can be safely removed as soon as the movable portion of the cover is out of 60 the way to give admission, for in both cases 65

this part of the cover cannot be swung to open position until the circuit has been opened.

It will be understood that the details of this construction may all be modified by 70 those skilled in the art without departing from the spirit of my invention.

I claim:—

1. The combination of a box, a stationary slab of non-conducting material dividing the 75 interior of said box into two compartments, a fuse mounted on one side of the slab in one compartment and a switch mounted on the other side of the slab in the other compartment, a manually operable handle pivotally mounted on one side of the box, means within the box connecting the handle to the switch, and a cover for the two compartments of the box comprising a segment of the cylinder whose axis coincides with that 80 of said handle.

2. The combination of a box, a stationary slab of non-conducting material dividing the interior of said box into two compartments, a fuse mounted on one side of the slab in one 90 compartment and a switch mounted on the other side of the slab in the other compartment, a manually operable handle pivotally mounted on one side of the box and means within the box connecting the handle to the 95 switch, and a two part cover for the box comprising a segment of the cylinder whose axis coincides with that of said handle, each of the compartments being closed by a different part of the cover, said handle having a 100 lateral extension substantially parallel to its axis and projecting over said cover.

3. The combination of a box, a stationary slab of non-conducting material dividing it into two compartments, a fuse mounted on one side of the slab in one compartment and a switch mounted on the other side of the slab in the other compartment, a manually operable handle pivotally mounted on one side of the box and means within the box 105 connecting the handle to the switch, a cover for the box comprising a segment of the cylinder whose axis coincides with that of said handle, and a cylindrical shield connected to said means and movable thereby 110 between said slab and cover.

4. The combination of a box, a stationary slab of non-conducting material substantially midway of the box dividing it into two compartments, a fuse mounted on one side of the slab in one compartment and a switch mounted on the other side of the slab in the other compartment, a manually operable handle pivotally mounted on one side of the box, means within the box connecting the handle to the switch, a cover for the two compartments of the box comprising a segment of a cylinder whose axis coincides with that of said handle, means to hold the handle in circuit closing position, and a spring 125 130

to move the handle to open circuit position, said handle having an extension substantially parallel to its axis and extending over said cover to prevent the cover being opened when the switch is closed.

5. The combination of a box, a stationary slab of non-conducting material dividing it into two compartments, fuses mounted on one side of the slab in one compartment and a switch mounted on the other side of the slab in the other compartment, means connecting the fuses to said switch electrically and also securing parts of the switch and the fuses to the slab, a manually operable han-

dle pivotally mounted on one side of the box, a bail within the box connecting the handle to the switch, a cover for the box comprising a segment of a cylinder whose axis coincides with that of said handle, means to hold the handle in circuit closing position, a spring 20 to move the handle to open circuit position, said handle having an extension substantially parallel to its axis and extending over said cover, and a cylindrical shield connected to said bail and movable thereby between said slab and cover. 25

HARRISON J. L. FRANK.
